CLAIM

The ornamental design for a hitch mountable flagpole, as shown and described.

DESCRIPTION

FIG. 1 is an isometric view of a hitch-mountable flagpole in the vertical position;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof;

FIG. 8 is a right side view of the hitch mountable flagpole in the first tipped position;

FIG. 9 is a left side view of the hitch mountable flagpole from FIG. 8;

FIG. 10 is a right side view of the hitch mountable flagpole in the second tipped position; and,

FIG. 11 is a left side view of the hitch mountable flagpole from FIG. 10.

The hitch mountable flagpole is shown with at least one symbolic break to indicate indefinite length. The appearance of any portion of the hitch mountable flagpole between the symbolic breaks shown in the figures illustrate portions of the hitch mountable flagpole that form no part of the claimed design. The broken lines illustrate portions of the hitch mountable flagpole that form no part of the claimed design.
